UNITED STATES PATENT OFFICE.

FRANK P. CAWLEY, OF PITTSBURGH, PENNSYLVANIA.

HAIR-DRYING DEVICE.

1,112,262.

Specification of Letters Patent. Patented Sept. 29, 1914.

Application filed September 30, 1912. Serial No. 723,106.

To all whom it may concern:

Be it known that I, FRANK P. CAWLEY, a citizen of the United States of America, residing at Pittsburgh, in the county of Allegheny and State of Pennsylvania, have invented certain new and useful Improvements in Hair-Drying Devices, of which the following is a specification, reference being had therein to the accompanying drawing.

10 This invention relates to a hair drying device, and the objects of my invention are, to provide an adjustable frame that can be easily placed upon the shoulders to support the hair in a position that permits of air 15 circulating through the same and quickly drying the hair, and to provide a simple and inexpensive drying frame that can be placed upon the shoulders to support the hair, the frame being constructed whereby 20 it can be rocked to move the hair and allow air to circulate through the same or fixed to permit of a person performing certain duties while the hair is drying.

Other objects of my invention are to provide a hair drying device that permits of 25 the hair being moved and shifted when drying the same in the sun or before a fire, without handling the hair with the hands, and to provide an adjustable hair supporting frame that prevents the hair from 30 contacting with the back and spoiling a garment.

Further objects of my invention are to provide a hair drying device embodying a 35 corrugated hair supporting member having upturned ends coöperating with the corrugations of said member in preventing the hair from becoming accidentally displaced therefrom, and to accomplish the above results by a mechanical construction that readily adapts itself to the shoulders without causing any inconvenience or special attention by the wear.

With the above and other objects in view 45 the invention resides in the novel construction, combination and arrangement of parts to be hereinafter specifically described and then claimed.

Reference will now be had to the drawing 50 wherein like numerals denote corresponding parts throughout the several views in which:—

Figure 1 is a side elevation of the hair 55 drying device, as applied to the shoulders, Fig. 2 is a plan of the same, Fig. 3 is an enlarged side elevation of a portion of the de-

vice, Fig. 4 is a front elevation of the same, Fig. 5 is a front elevation of a portion of a modified form of device, Fig. 6 is a side elevation of another modified form of device, Fig. 7 is a side elevation of a further modification of the invention, and Fig. 8 is a plan of a still further modification of the invention.

A hair drying device in accordance with 65 this invention comprises shoulder pieces, arms, and a hair supporting frame. The shoulder pieces are designated 1 and are made of a single piece of wire bent whereby the shoulder pieces will conform to the 70 shoulders of the body. The shoulder pieces are connected by a breast piece 2 and this breast piece can be connected to a garment 3 by a cord 4, pin or other fastening device. The shoulder pieces 1 have the rear ends 75 thereof twisted or otherwise connected together, as at 5 with one end of a shoulder piece terminating in an eye 6. The twisted ends of the shoulder pieces are vertically 80 disposed and extending through the eye 6 is a screw 7 provided with a nut 8. The screw 7 and the nut 8 retain eyes 9 frictionally in engagement with the eye 6, and the eyes 9 form part of the lower termini of one of the arms designated 10. The inner ends of the arms are also vertically 85 disposed and clamped together by a sleeve 11. The arms 10 are segmental in plan and the outer ends thereof are radially disposed, as at 12 to hold the corrugated or scalloped 90 hair supporting member 13 spaced from the arms 10. The ends of the member 13 are formed integral with the ends of the arms 10 and are bent upwardly, as at 14 to co-operate with the corrugated or scalloped 95 frame in retaining the hair upon said member. The hair supporting member coöperates with the arms 10 in forming a segment-shaped skeleton structure that extends 100 rearwardly from the back of the neck and supports the hair away from the body, as shown in Fig. 1. It is through the medium of the pivot between the arms 10 and the shoulder pieces 1 that the hair supporting member can be positioned at a desired angle 105 to correctly support the hair whereby air can circulate through the same.

In Figs. 5 and 6 the pivot connection fastening the shoulder pieces and the arms 10 is dispensed with and the ends of the arms 110 and the ends of the shoulder pieces connected by a sleeve 15 that is mounted upon the

ends of said arms and the ends of said shoulder pieces. The sleeve 11 is also dispensed with and the ends of the arms twisted, as at 16.

5 In Fig. 7 the shoulder pieces and arms are made of the same piece of wire and the vertical portion between the shoulder pieces and arms formed by twisting the wire together, as at 17.

10 As illustrated in Fig. 8 the breast piece 2 can be dispensed with.

From the foregoing it will be observed that I have devised a corrugated or scalloped segment-shaped adjustable hair supporting frame that is provided with means whereby it can be supported at the rear of the body from the shoulders thereof, and furthermore, that the device can be made of a single piece of wire to serve the same purpose as the device made of more than one piece of wire and having certain adjustments.

15 While in the drawing there are illustrated the preferred embodiments of my invention, it is to be understood that the structural elements are susceptible to such changes, as in size, shape and manner of assemblage as fall within the scope of the appended claims.

20 What I claim is—

25 1. A hair drying device comprising a segment-shaped corrugated member adapted to be supported from the shoulders, the corrugations of said member being segment-shaped in plan and extending inwardly and outwardly with respect to each other, said member having each of its ends extending upwardly, said ends being disposed at right angles with respect to said corrugations.

2. A hair drying device comprising a seg-

ment-shaped corrugated member adapted to be supported from the shoulders, the corrugations of said member being segment-shaped in plan and extending inwardly and outwardly with respect to each other, said member having each of its ends extending upwardly, said ends being disposed at right angles with respect to said corrugations, shoulder pieces to said upturned ends of said member.

3. A hair drying device comprising a segment-shaped corrugated member adapted to be supported from the shoulders, the corrugations of said member being segment-shaped in plan and extending inwardly and outwardly with respect to each other, said member having each of its ends extending upwardly, said ends being disposed at right angles with respect to said corrugations, shoulder pieces, means for connecting the shoulder pieces to said upturned ends of said member, and a breast piece connecting said shoulder pieces.

4. A hair drying device comprising a segment-shaped corrugated member, means adapted to be mounted upon the shoulders of a person for supporting said member above the shoulders and spaced from the neck of a person, the ends of said member being extended upwardly and disposed at right angles with respect to the corrugations of said member.

5. In testimony whereof I affix my signature in the presence of two witnesses.

FRANK P. CAWLEY.
